ELECTRONIC CONTROL SYSTEM

Edward F. Nowak, Hartford, Conn., assignor to
 Federal Electric Products Company, Newark,
 N. J., a corporation

Application August 21, 1948, Serial No. 45,537

14 Claims. (Cl. 318—317)

1

The present invention relates to electronic control systems for motor or other loads operable by direct current obtained from an alternating current source.

One object of the invention is the provision of a system wherein the control circuits are isolated, electrically, from the power circuits.

Another object is the provision of a motor control system which provides an exceedingly quick-acting control of the motor speed so as to maintain constant motor speed, comparable to constant speed characteristic of a synchronous motor, and to eliminate hunting.

A further object is to provide a control circuit for firing grid-controlled rectifiers by pulses from auxiliary rectifiers, the magnitude of the pulses being considerably greater than required, thereby permitting one design of control circuit to be used in control systems of a wide range of sizes or current ratings.

A further object is the provision of a fail-safe electronic motor-control circuit, precluding increase in the speed of the motor in the event of defective control or control failure.

Another object is the provision of a control circuit wherein a glow-discharge tube is utilized for limiting the load current, whereby a sharp current-limiting action is obtained. Further, in connection with this object of the invention, the glow-discharge tube provides a visual indication of overloading.

At the present time existing control systems of the general type to which this invention relates are not entirely satisfactory because they have one or more of the following objections and disadvantages:

1. A control device, such as a saturable reactor is used and its inherent inductive lag causes the control to respond slowly. This is particularly objectionable under conditions of rapidly changing load.

2. The auxiliary control tubes are not isolated electrically from the power tubes. This usually results in poor auxiliary tube performance.

3. Failure of an auxiliary control tube causes an unsafe condition, i. e. a motor speed which may be many times higher than the desired preset speed.

4. If the main power tubes are of the mercury vapor type, changes in ambient temperature affect their characteristics to the point where performance of the control is impaired.

The control system of the present invention overcomes these disadvantages of existing control systems. There is no saturable reactor to

2

slow the response; instead the main power tubes are fired through pulse transformers by small inert gas thyratrons, which are in turn controlled, preferably by the quadrature method. In this way, the auxiliary control tubes are isolated electrically from the main power tubes, resulting in improved performance. The auxiliary control tubes are so arranged that a failure of any of them will not result in a condition that will increase the conductivity of the main power tubes, therefore the control will always fail safe. Since the small thyratrons which fire the main power tubes are of the inert gas type, they are not adversely affected by temperature changes. Since the main power tubes will always fire when the small thyratrons fire, the main power tubes can be of the mercury vapor type and the performance of the control will not be adversely affected by temperature changes. In addition, this control system provides other useful features including a novel current limiting circuit utilizing the breakdown of a glow discharge device. This provides a very sharp action, as well as providing a visual indication of the current limiting action, the advantages of which are obvious. The accomplishment of these results constitutes an object of the present invention.

The above and other objects, features and advantages of this invention, as well as objects ancillary thereto, will be fully understood from the following description considered in connection with the accompanying illustrative drawings:

In the accompanying drawings:

Fig. 1 is a circuit diagram of the presently preferred embodiment of the invention;

Figs. 2a, 2b, 2c and 2d are graphic illustrations of the concomitant discharge or firing of the control and power tubes;

Fig. 3 is a diagram illustrating the discharge or firing of certain of the tubes by the quadrature method;

Figs. 4 and 5 are graphic illustrations of the power-output action of the power tubes.

Power is supplied by the transformer secondary T1S! to the motor armature MA through a full wave rectifier consisting of electric valves V1 and V2, which are controlled grid rectifiers. Transformer secondary T2S! provides a hold-off voltage so that with no signals from transformer secondaries T3S and T4S, electric valves V1 and V2 do not conduct for any portion of the cycle. A pulse from transformer secondary T3S will fire electric valve V1, and a pulse from transformer secondary T4S will fire electric valve V2. So by controlling the point in each cycle that the trans-

former pulses occur, the point in the cycle at which electric valves V_1 and V_2 begin to conduct can be controlled, thereby controlling the armature voltage. Condensers C_1 and C_2 are used to drain off any excess charge from the grids of electric valves V_1 and V_2 to prevent mis-firing. Resistances R_1 and R_2 are used to limit the grid current of electric valves V_1 and V_2 . Resistances R_3 and R_4 are used to load transformer secondaries T_3S and T_4S to prevent excessively high voltages. Pulses appear across transformer secondaries T_3S and T_4S , of course, when their respective transformer primaries, T_3P and T_4P are energized. Transformer primaries T_3P and T_4P are energized by transformer secondary T_3S4 through the auxiliary grid-controlled rectifier valves V_8 and V_9 . These last mentioned valves are smaller than the power supply valves V_1 and V_2 .

Figs. 2a, 2b, 2c and 2d are graphic illustrations of this pulse firing, showing two sets of operating conditions for tubes V_8 and V_1 respectively. Tubes V_2 and V_9 operate in the same manner on the other half cycle. The point in the cycle at which electric valves V_8 and V_9 , and therefore electric valves V_1 and V_2 , are fired is determined by the grid control of electric valves V_8 and V_9 , according to the quadrature method. The control is accomplished by applying to the grids a voltage of anode frequency but lagging the anode voltage by 90 electrical degrees. Under this condition, as shown in Fig. 3, the grid voltage will reach the critical value, that which starts tube conduction, when the anode voltage is approximately maximum and the tubes will conduct for approximately one-half of each positive half cycle of anode voltage indicated by the shaded area. A direct current voltage of variable magnitude and polarity is inserted in series with the quadrature voltages. By controlling the magnitude and polarity of this direct current voltage, it is possible to control the output of the thyratrons. This is illustrated in Figs. 4 and 5. If the direct current voltage is zero, the same condition exists as in Fig. 3 and the thyratrons conduct approximately one-half of each cycle. If the direct current voltage is made positive and of a magnitude equal to the peak value of the quadrature voltage the condition is as shown in Fig. 4 and the thyratrons conduct for the entire cycle. If the direct current voltage is made negative and of a magnitude equal to the peak value of the quadrature voltage, the condition is as shown in Fig. 5 and the thyratrons do not conduct for any part of the cycle. Therefore, by varying this direct current voltage from the negative maximum to the positive maximum it is possible to control the thyratrons from "full on" to "full off".

Transformer secondary T_2S3 provides the alternating current voltage which is shifted in phase by resistance R_{25} and condenser C_{10} . Resistances R_{23} and R_{24} form a divider network for this quadrature voltage. Resistances R_{26} and R_{27} are used to limit the grid current of electric valves V_8 and V_9 . Condensers C_{11} and C_{12} are used to drain any excess charge from the grids of electric valves V_8 and V_9 . The direct current voltage, variable in magnitude and polarity, which controls electric valves V_8 and V_9 by the quadrature method is obtained from the bridge consisting of electric valve V_6 and resistances R_{18} , R_{19} and R_{20} . Valve V_6 is a vacuum triode. This bridge is supplied with a direct current voltage from a voltage doubler rectifier consisting of transformer secondary T_2S2 , resistance R_{22} ,

rectifiers DDR_1 , DDR_2 , resistance R_{21} , condensers C_8 and C_9 . The output voltage of this voltage doubler is stabilized by the voltage regulator tube V_7 which is a glow-discharge tube. 5 This stabilized voltage is also used as a reference voltage which is applied to potentiometer R_{15} .

The magnitude and polarity of the output voltage of the bridge is controlled by the condition of conductivity of electric valve V_6 , which is in turn dependent upon the grid to cathode potential of said valve V_6 . Thus, a change in the grid to cathode potential of valve V_6 changes the output voltage of the bridge, which changes the point in the cycle at which auxiliary valves V_8 and V_9 are fired and therefore changes the point in the cycle at which power valves V_1 and V_2 are fired. The entire system is so sensitive that a change of approximately 0.3 volt in the grid to potential of valve V_6 will change electric valves V_1 and V_2 from the condition of no conductivity to full conductivity.

The voltage components which make up the grid to cathode voltage of electric valve V_6 are the voltage across resistance R_6 , which is proportional to the terminal voltage of the motor armature, the voltage across resistance R_{11} , which opposes the voltage across resistance R_6 and therefore compensates for the IR drop of the armature, and the voltage across resistance R_{14} , 10 which is proportional to the setting of resistance R_{15} which is the speed setting for armature control. Valve V_5 is a vacuum triode and is normally at full and constant conductivity. The voltage difference between the voltage across resistance R_6 and the voltage across resistance R_{11} is compared with the reference voltage across resistance R_{14} , 15 and then electric valve V_6 acts to operate the circuits described above to control the condition of conductivity of electric valves V_1 and V_2 so as to keep the counter E. M. F. of the armature, 20 and therefore its speed, assuming constant field excitation, at the desired value as set on resistance R_{15} .

The voltage across resistance R_{11} , which is 25 proportional to armature current, is obtained in the manner which will now be described. Current transformer T_5 has its split primaries T_5P_1 and T_5P_2 in the anode leads of electric valves V_1 and V_2 so that alternate half-cycles of current create an alternating flux in its core. Although these primaries are shown in the anode leads, they will function equally as well in the cathode leads. This alternating flux produces an alternating current voltage in the transformer secondary T_5S . The output of transformer secondary T_5S is rectified by a full wave rectifier V_3 . Resistance R_8 is used to prevent excessively high voltages across transformer secondary T_5S . Resistances R_{11} and R_{12} form a simple divider 30 network across the output of the rectifier so that the voltage across resistance R_{11} is proportional to the output of the rectifier and therefore to the armature current.

Resistance R_{10} and electric valve V_4 form the 35 principal elements of the current limiting system. Electric valve V_4 which is normally non-conducting is a glow-discharge device such as a neon lamp. The voltage applied to electric valve V_4 is varied by changing the setting of resistance R_9 . Electric valve V_4 will break down 40 at various values of armature current depending on the setting of resistance R_9 , which is the current-limit setting. When electric valve V_4 breaks down, it provides a visual indication that the armature current has reached the pre-set limit.

In addition, it allows current to flow through resistance R10 which is in the grid-cathode path of both electric valves V5 and V6. This changes the conductivity of electric valve V6 directly, due to the appearance of a voltage across resistance R10, and indirectly by the change in conductivity of electric valve V5 which changes the voltage across resistance R16 which in turn changes the grid-cathode potential of electric valve V6. These effects acting together are sufficient to change the conductivity of electric valve V6, which in turn operates through previously described circuits to decrease the conductivity of electric valves V1 and V2 and limit the armature current to substantially the preset value regardless of the degree of the over-load, including a locked armature.

Condenser C3 is used to filter the voltage across resistance R10, and C4, C5 and C6 are by-pass condensers. C6 and R16 act to filter the alternating current component of the voltage across R6. R16 together with R17 act as current limiting resistances of the grid of V6.

The motor-field control will now be described:

Power is supplied by the transformer secondary T1S2 to the motor field MF through a full wave rectifier, consisting of electric valves V11 and V12 which are controlled grid rectifiers. The grids of electric valves V11 and V12 are controlled directly by the quadrature method without auxiliary gas tubes as in the armature control. This is quite acceptable here, because the motor is protected from loss of field by the field failure relay FFCR. It will be readily understood that a failure of an auxiliary tube which will increase the field voltage to full value, will not result in an unsafe condition. Transformer secondary T2S6 provides the alternating current voltage which is shifted in phase by resistance R38 and condenser C16, resistances R36 and R37 form a divider network for this quadrature voltage. Resistances R39 and R40 are used to limit the grid current of electric valves V11 and V12. The direct current voltage, variable in polarity and magnitude, which is used to control electric valves V11 and V12 by the quadrature method is obtained from the bridge made up of resistances R31, R32, R33 and electric valve V10, the latter being a vacuum triode. The voltage supply for this bridge is provided by the voltage doubler rectifier consisting of transformer secondary T2S5, resistance R29, rectifiers DDR3, DDR4, condensers C13, C14 and resistance R30.

Resistances R41 and R42 form a simple divider network across the field so that the voltage across resistance R41 is proportional to the field voltage of the motor. The grid to cathode voltage of electric valve V10 is made up of the voltage as set by resistance R35 (field voltage setting) and the voltage across resistance R41. Electric valve V10 compares these two voltages which are in opposition, and when the voltage across resistance R41 differs from that set by resistance R35, the conductivity of electric valve V10 is changed, which in turn changes the conductivity of electric valves V11 and V12, to return the field voltage to its desired preset value.

The coil of the current sensitive relay FFCR is placed in series with the field MF and its contact interlocks the 3 wire magnetic control of the armature contactors, so that the armature can remain energized only when the field is energized. The contact of a time delay relay, TD, is also placed in series with the field so that neither the field nor the armature can be energized

until the tube cathodes have been energized for a sufficient time to reach the proper operating temperature. The magnetic control (three wire, reversing) and the dynamic braking which includes the resistance R5 and the relays CRF and CRR are conventional and therefore need not be described. OL designates the heater of the usual thermal overload relay the normally closed contacts of which are indicated at OLC.

The auxiliary relay CRA is arranged so that it is energized when either of the directional contactors are energized. One normally closed contact CRA1 of CRA is used to short circuit parts of resistance R35 so that when CRA is deenergized, the field voltage is at full value, regardless of the setting of the field voltage control. This assures starting at full field. At starting when CRA is energized, this normally closed contact opens, but condenser C15 has assumed a charge which puts the field value at full until this charge is drained off by resistance R34. This results in full field starting with a gradual return to the preset value of field voltage. The other normally closed contact CRA2 of CRA short circuits resistance R19 when CRA is deenergized. This means that V1 and V2 are non-conducting and when the directional contactor and CRA are energized at starting this contact opens, and the voltage across resistance R19 increases gradually as condenser C7 discharges. This insures a smooth start without excessive armature current. An extra contact SB1 of the stop button SB is inserted between resistance R20 and resistance R21. When the stop button is depressed this opens causing the output of the bridge to be negative and thus causing V1 and V2 to be non-conducting. This happens before relays CRF or CRR can operate, therefore relays CRR and CRF are not required to rupture the armature current.

Thus it is seen that the system hereinbefore described is well adapted to accomplish the several objects of the invention. It will be understood however that various changes may be made without departing from the underlying idea or principles of this invention within the scope of the appended claims.

Having thus described my invention, what I claim and desire to secure by Letters Patent, is:

1. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is operatively connected to said control electrode-means of said first mentioned valve means for effecting the conduction of the latter, said second valve means having control electrode-means for determining the instant of conduction thereof, and means including phase-shifting means for energizing said last mentioned control electrode-means in predetermined phase relation with the anode means of said second valve means.

2. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected to said control means of said first mentioned valve means, said second valve means

having control electrode-means for determining the instant of conduction thereof, means for impressing on said last mentioned control means a composite voltage comprising voltage which is in quadrature phase relation with the anode means of said second valve means and a direct current voltage variable in polarity and amount in series with said quadrature voltage.

3. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected by transformer means to said control means of said first mentioned valve means, said second valve means having control electrode-means for determining the instant of conduction thereof, means for impressing on said last mentioned control means a composite voltage comprising voltage which is in quadrature phase relation with the anode means of said second valve means and a direct current voltage variable in polarity and amount in series with said quadrature voltage.

4. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected to said control means of said first mentioned valve means, said second valve means having control electrode-means for determining the instant of conduction thereof, means for impressing on said last mentioned control means a voltage which is in quadrature phase relation with the associated anode means, and means for supplying a direct current voltage variable in polarity and amount in series with said quadrature voltage, said last mentioned means comprising a bridge including uni-directional electrical valve means in one circuit thereof.

5. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected by transformer means to said control means of said first mentioned valve means, said second valve means having control electrode-means for determining the instant of conduction thereof, means for impressing on said last mentioned control means a voltage which is in quadrature phase relation with the associated anode means, and means for supplying a direct current voltage variable in polarity and amount in series with said quadrature voltage, said last mentioned means comprising a bridge including uni-directional electrical valve means in one circuit thereof.

6. In an electronic control system for a load operable by direct current, means including uni-directional electrical valve means for supplying to said load direct current derived from an alternating current source, said valve means including control electrode-means operable to determine the instant of conduction of said valve means,

means for impressing on said control means an alternating current voltage which is out of phase in relation to the anode voltage of said valve means, and means for supplying in series with said voltage a direct current of variable amount and polarity, said last mentioned means comprising a bridge including uni-directional electrode-controlled electrical valve means in one circuit thereof.

10 7. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected to said control means of said first mentioned valve means, said second valve means having control electrode-means for determining the instant of conduction thereof, means for impressing on said last mentioned control means a voltage which is in quadrature phase relation with the associated anode means, means for supplying a direct current voltage variable in polarity and amount in series with said quadrature voltage, and means including a glow discharge tube operable under the control of the current through said load and acting through said direct current voltage supply means and said second valve means to limit the current supplied to said load.

35 8. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected to said control means of said first mentioned valve means, said second valve means having control electrode-means for determining the instant of conduction thereof, means for impressing on said last mentioned control means a voltage which is in quadrature phase relation with the associated anode means, means for supplying a direct current voltage variable in polarity and amount in series with said quadrature voltage, said last mentioned means comprising a bridge including uni-directional electrical valve means in one circuit thereof, means for providing a reference voltage, means for providing a voltage proportional to the terminal voltage of said load, and means for providing a voltage opposite to said terminal voltage and proportional to the voltage drop across the load, the output of said valve of the bridge being controlled by the difference between said two last mentioned voltages and by said reference voltage.

60 9. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is operatively connected to said control electrode-means of said first mentioned valve means for effecting the conduction of the latter, said second valve means having control electrode-means for determining the instant of conduction thereof, and means including phase-shifting means for energizing said last mentioned control electrode-means in predetermined phase relation with the

anode means of said second valve means, said second valve means being of the inert gaseous type and said first mentioned valve means being of the mercury vapor type.

10. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is operatively connected to said control electrode-means of said first mentioned valve means for effecting the conduction of the latter, said second valve means having control electrode-means for determining the instant of conduction thereof, and means including phase-shifting means for energizing said last mentioned control electrode-means in predetermined phase relation with the anode means of said second valve means, said second valve means having a smaller power output than said first valve means.

11. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected by transformer means to said control means of said first mentioned valve means, said second valve means having control electrode-means for determining the instant of conduction thereof, means for impressing on said last mentioned control means a composite voltage comprising voltage which is in quadrature phase relation with the anode means of said second valve means and a direct current voltage variable in polarity and amount in series with said quadrature voltage, said second valve means being of the inert gaseous type and said first mentioned valve means being of the mercury vapor type.

12. In an electronic control system for a load operable by direct current, means including uni-directional electric valve means for supplying uni-directional current to said load from a source of alternating current, said valve means having control electrode-means therein for determining the instant of conduction thereof, uni-directional electric valve means the output circuit of which is connected by transformer means to said control means of said first mentioned valve means, said second valve means having control electrode-means for determining the instant of conduction

thereof, means for impressing on said last mentioned control means a composite voltage comprising voltage which is in quadrature phase relation with the anode means of said second valve means and a direct current voltage variable in polarity and amount in series with said quadrature voltage, said second valve means having a smaller power output than said first valve means.

13. A control system, comprising a gaseous rectifier which is grid controlled by pulses from the secondary winding of a transformer, said control system comprising a source of alternating current and an auxiliary gaseous rectifier connected in series with the primary of said transformer, a source of alternating current phase shifted approximately 90° behind the anode voltage of said auxiliary rectifier, a source of direct current voltage variable in magnitude and polarity superimposed on said phase shifted voltage and said phase shifted voltage with the superposed direct current voltage connected between the grid and cathode of said auxiliary rectifier to convert a small change in direct current voltage to a change in phase of 0 to 180° of the said pulses.

14. A control system for a direct current motor, controlled-grid rectifier means for supplying current for operating said motor from an alternating current source, auxiliary controlled-grid rectifier means operatively connected to said first rectifier means for supplying pulses to the latter for determining the instant of conduction of said first rectifier means, means for providing a reference voltage, means for providing a voltage proportional to the terminal voltage of said motor, means for providing a voltage opposed to said terminal voltage and proportional to the armature current of said motor, and means operatively connected to the grid-control means of said auxiliary rectifier means and operable in response to the difference between said reference voltage and the resultant of said last two mentioned voltages for determining the instant of conduction of said auxiliary rectifier means.
